[57] CLAIM

The ornamental design for a cutting tip wrench, as shown and described.

DESCRIPTION

FIG. 1 is a perspective view of a cutting tip wrench showing our new design;

FIG. 2 is a front view of the cutting tip wrench;

FIG. 3 is a left side view of the cutting tip wrench;

FIG. 4 is a top view of the cutting tip wrench;

FIG. 5 is a bottom view of the cutting tip wrench;

FIG. 6 is a cross-sectional view of the cutting tip wrench taken along line 6—6 in FIG. 3; and,

FIG. 7 is a cross-sectional view of the cutting tip wrench taken along line 7—7 in FIG. 3.

The rear view of the cutting tip wrench is identical to the front view of FIG. 2. The right side view of the cutting tip wrench is identical to the left side view of FIG. 3.
